CONVERSION OF HYDROCARBON OILS -

Kenneth Swartwood, Chicago, Ill., assignor to
Universal Oil Products Company, Chicago, Ill.,
a corporation of Delaware

Application December 24, 1934, Serial No. 758,996

14 Claims. (Cl. 196—49)

This invention particularly refers to an improved process for the pyrolytic conversion of hydrocarbon oils accompanied by reduction of the residual liquid conversion products of the process to substantially dry coke at relatively high temperature wherein the vaporous products resulting from said conversion and the vaporous products resulting from the coking operation are commingled and subjected to continued conversion without additional heating for the purpose of materially improving the yield and quality of the final motor fuel product of the process.

A recent development in the coking of relatively heavy oils, such as, for example, residual liquids resulting from the conversion of lower boiling oils, which promises to merit wide adoption in the petroleum industry comprises subjecting the oil in a heating coil to a conversion temperature of the order of 950 to 1000° F., or at least 15 sufficiently high to effect its subsequent reduction to coke, without allowing it sufficient time in the heating coil to permit the excessive formation and deposition of coke therein. Actual reduction of the highly heated residual oil to coke 20 is usually accomplished in an enlarged coking chamber following the heating coil which may be operated at any desired pressure ranging from substantially atmospheric to a superatmospheric pressure of the order of several hundred pounds 25 per square inch. Operations of this character normally produce a coke of more uniform quality and lower volatility than is obtained by coking methods previously in vogue, due to the relatively high temperature to which the oil to be coked is heated as well as to the fact that the 30 entire mass of material to be coked receives substantially uniform heat treatment. It is also believed that the use of relatively high superatmospheric pressures in the coking zone, which 35 favor reduction of the residual liquids to coke by cracking, help to produce a coke of better and more uniform quality. Heretofore, one of the chief disadvantages in this method of coking has been the high temperature of the vaporous products evolved during the coking operation which necessitates large fractionating and/or other cooling equipment.

The present invention employs the method of coking above outlined for the reduction of the 40 residual liquid products of the cracking operation to coke and in addition utilizes to advantage the excess heat contained in the vaporous products from the coking operation by commingling the same with the vaporous products resulting from the cracking operation and previously separated

from said residual liquids subjected to coking, the commingled vaporous products being subjected to continued conversion in a reaction chamber maintained at substantial superatmospheric pressure without additional heating. 5

In one specific embodiment, the invention comprises subjecting hydrocarbon oil to conversion conditions of elevated temperature and superatmospheric pressure in a heating coil and communicating reaction chamber, separating the resulting vaporous and residual liquid conversion products, heating said residual liquid in a heating coil to a temperature sufficiently high to effect its subsequent reduction to coke without allowing it sufficient time in the heating coil to 10 permit any excessive formation and deposition of coke in this zone, introducing the highly heated residual liquid into a coking chamber maintained at substantial superatmospheric pressure wherein it is reduced to coke, commingling 15 the hot vaporous products from the coking chamber with said vaporous conversion products, subjecting the commingled materials to continued conversion in a separate reaction chamber maintained at substantial superatmospheric pressure, 20 separating the resulting vaporous and liquid conversion products, subjecting the latter to further vaporization at substantially reduced pressure, returning the resulting residual liquid to the heating coil of the coking system, subjecting the 25 vaporous products of the process, including those evolved by said further vaporization, to fractionation whereby their insufficiently converted components are condensed as reflux condensate, returning the reflux condensate to the first mentioned heating coil for further conversion, subjecting fractionated vapors of the desired end-boiling point to condensation and collecting and 30 separating the resulting distillate and gas. 35

Charging stock of any desired type may be employed and, depending upon its characteristics, may be supplied direct to the heating coil of the cracking system, to the heating coil of the coking system, to the fractionator or to the vaporizing chamber following the last mentioned reaction chamber of the system. 40

The accompanying diagrammatic drawing illustrates one form of apparatus for carrying out the invention. Referring to the drawing, heating coil 1 is located within a furnace 2 of any suitable form and the oil supplied thereto for conversion, in the manner to be later more fully described, is subjected by means of heat supplied from the furnace to the desired conversion temperature, preferably at a substantial superat- 50 55

mospheric pressure; the heated products being discharged from the heating coil through line 3 and valve 4 into reaction chamber 5.

Reaction chamber 5 is also preferably maintained at a substantial superatmospheric pressure and, although not indicated in the drawing, is preferably insulated to prevent the excessive loss of heat therefrom by radiation so that continued conversion of the heated products supplied to this zone, and particularly their vaporous components, is accomplished therein. In the particular case here illustrated, the stream of hot conversion products from heating coil 1 is introduced into the lower portion of chamber 5 wherein vaporous and liquid conversion products separate; the vaporous products passing upward through the chamber to be directed therefrom through line 6 and valve 7 to reaction chamber 8, while the residual liquid conversion products are withdrawn from the lower portion of chamber 5 through line 9 and valve 10 to pump 11, by means of which they are supplied through line 12, valve 13 and line 14 to heating coil 15. It will be understood, of course, that the invention is not limited to the particular flow through the reaction chamber illustrated in the drawing. For example, the stream of hot conversion products from heating coil 1 may enter the upper portion of the reaction chamber, in which case both vaporous and liquid conversion products may pass downward through the chamber to be separately withdrawn from its lower portion, thus affording the liquid products a somewhat longer continued conversion time in the reaction chamber. Other well known alternative methods of flow through the reaction chamber may be employed within the scope of the present invention although, for the sake of simplicity, they are not here illustrated. However, such alternatives are not to be considered equivalent in all cases but may be selected to suit requirements. In any event, the vaporous and liquid products resulting from conversion in heating coil 1 and reaction chamber 5 are preferably separated at substantial superatmospheric pressure, the residual liquid products being supplied to heating coil 15 while the vaporous products are supplied to reaction chamber 8 for further conversion.

A furnace 16 of suitable form supplies the required heat to the relatively heavy oil passing through heating coil 15 to heat the same to a temperature sufficient to effect its subsequent reduction to coke in coking chamber 19, to which the stream of heated oil is supplied through line 17 and valve 18, without allowing the oil sufficient time in heating coil 15 to permit any excessive formation and deposition of coke in this zone and in the line communicating with the coking chamber. Preferably, relatively high rates of heating and relatively high velocities are employed in heating coil 15 to accomplish the desired results. However, this method of coking heavy oils is not new, per se, with the present invention and need not therefore be considered here in any great detail.

Coking chamber 19 is also preferably operated at a substantial superatmospheric pressure which may be substantially the same, somewhat higher or somewhat lower than the pressure employed in reaction chamber 5. Although only one point of introduction for the materials to be coked into chamber 19 is illustrated in the drawing it will be understood that they may be supplied thereto at any desired point or plurality of points in this zone. Sufficient time is afforded the highly

heated relatively heavy oils supplied to chamber 19 from heating coil 15 to effect their reduction to substantially dry coke in this zone, the coke being allowed to accumulate within the chamber to be removed therefrom in any well known manner, not illustrated, after the operation of the chamber is completed and preferably after it has been isolated from the rest of the system. Chamber 19 is provided with a suitable drain-line 20 controlled by valve 21 which may also serve, when desired, as a means of introducing steam, water or other suitable cooling medium into the chamber after its operation is completed and after it has been isolated from the rest of the system in order to hasten cooling and facilitate cleaning of the chamber. It is, of course, also within the scope of the present invention, although only one coking chamber is shown in the drawing, to employ a plurality of such zones, one or more of which may be operated while another or others are being cleaned and prepared for further operation so that the duration of the operating cycle of the process is not limited by the capacity of the coking zone.

In accordance with the provisions of the present invention hot vaporous products resulting from the coking operation in chamber 19 are withdrawn therefrom through line 22 and valve 23 and are commingled in line 6 with the vaporous conversion products from reaction chamber 5, the commingled materials entering a separate reaction chamber 8, also preferably maintained at a substantial superatmospheric pressure, wherein they are subjected to continued conversion without additional heating. Chamber 8 is also preferably insulated to minimize loss of heat by radiation, although this is not indicated in the drawing.

In the case here illustrated, the commingled vaporous products from the first reaction chamber and from the coking zone enter the upper portion of reaction chamber 8 and are subjected to predetermined continued conversion time as they pass downward through this zone, the resulting vaporous and liquid conversion products being withdrawn in commingled state from the lower portion of chamber 8 through line 24 and supplied through valve 25 to vaporizing chamber 26. It is, however, within the scope of the present invention to employ any other desired flow through chamber 8 which will afford the commingled vapors appreciable continued conversion time in this zone and the vaporous and liquid conversion products may, when desired, be separately withdrawn from chamber 8, although such alternative means are not shown in the drawing.

Vaporizing chamber 26, in the case here illustrated, comprises the lower portion of column 27, the upper portion of which comprises fractionator 28, although separate structures may be employed, when desired, for the vaporizing and fractionating zones. Vaporizing chamber 26 is preferably maintained at a substantially reduced pressure relative to that employed in reaction chamber 8 whereby further vaporization of the liquid conversion products supplied to this zone from chamber 8 is accomplished. When vaporous and liquid conversion products are supplied to chamber 26 it also serves as a zone of final separation for these materials. The residual liquid conversion products remaining unvaporized in chamber 26 are withdrawn therefrom through line 29 and valve 30 to pump 31 by means of which they are fed through line 32 and may be

directed either through valve 33 in this line and through line 14 to heating coil 15 for further heating and subsequent reduction to coke, together with the residual liquid conversion products from chamber 5, or a regulated portion or all of the residual liquid products from chamber 26 may be diverted from line 32 through line 34 and valve 35 into line 17 to be directed therefrom into coking chamber 19 together with the stream 5 of highly heated products from heating coil 15 or the residual liquid products from chamber 26 may, when desired, be separately supplied, all or in part, direct to coking chamber 19 at any desired point in this zone by well known means not 10 shown in the drawing or a regulated portion or all of this material may be withdrawn from the system, as one of the final products of the process, through line 65 and valve 66 to cooling and storage or elsewhere as desired.

20 The final vaporous conversion products of the process pass, in the case here illustrated, from vaporizing chamber 26 through partition 36 into fractionator 28 wherein their insufficiently converted components are condensed as reflux condensate. The reflux condensate formed in fractionator 28 may be allowed to collect within the lower portion of this zone above deck or partition 36 to be withdrawn therefrom through line 37 and valve 38 to pump 39, by means of which 25 30 it is returned through line 40, valve 41 and line 42 to heating coil 1, for further conversion, in the manner already described.

Fractionated vapors of the desired end-boiling point are withdrawn, together with uncon- 35 densable gas produced by the process, from the lower portion of fractionator 28 through line 43 and valve 44 and are subjected to condensation and cooling in condenser 45. The resulting distillate and gas passes through line 46 and valve 40 47 to collection and separation in receiver 48. Uncondensable gas may be released from the receiver through line 49 and valve 50. Distillate may be withdrawn from receiver 48 through line 51 and valve 52 to cooling and storage or to any 45 desired further treatment. When desired, a regulated portion of the distillate collected in receiver 48 may be recirculated, by well known means, now shown in the drawing, to the upper portion of fractionator 28 to serve as a refluxing 50 and cooling medium in this zone for assisting fractionation of the vapors and to maintain the desired vapor outlet temperature from the fractionator.

As previously indicated, the present invention 55 permits the use of any desired type of hydrocarbon oil charging stock ranging from crude petroleum, topped or reduced crude and the like to heavy residual oils, including all of the various crude oil fractions such as straight-run gasoline, 60 naphtha, kerosene or kerosene distillate, gas oil, fuel oil and the like or mixtures of such materials as well as various cracked products such as pressure distillate, pressure distillate bottoms, reflux condensates and cracked residual oils. The charging 65 stock is supplied, in the case here illustrated, through line 53 and valve 54 to pump 55 by means of which it is fed through line 56 and may be supplied, all or in part, through line 57 and valve 58 into fractionator 28 or through line 70 59 and valve 60 into vaporizing chamber 26 or through line 61, valve 62 and line 14 to heating coil 15 or from line 61 through line 63, valve 64 and line 42 to heating coil 1, the method 75 of supplying the charging stock to the system depending, primarily, upon its characteristics.

Preferably, only charging stock of relatively high-boiling characteristics is supplied direct to heating coil 15 and only charging stock of relatively low-boiling characteristics is supplied direct to heating coil 1. Charging stock of any desired 5 characteristics may be supplied to the fractionator so long as it contains no appreciable quantity of high-boiling components of a high coke-forming nature unsuitable for conversion in heating coil 1 and no appreciable quantity of low-boiling fractions within the range of the desired 10 final motor fuel product of the process but of unsatisfactory quality, particularly with respect to antiknock value, the latter qualification also applying to any charging stock supplied to vaporizing chamber 26, although this is the only 15 limitation with respect to the type of charging stock which may be supplied to this zone.

The preferred range of operating conditions 20 which may be employed in the practice of the present invention in an apparatus of the general character illustrated and above described may be approximately as follows: The heating coil of the cracking system may employ an outlet conversion temperature ranging, for example, from 850 to 1050° F., preferably with a substantial superatmospheric pressure at this point in the system of from 100 to 500 pounds, or more, per square inch. Any desired pressure within substantially 25 the same range but no greater than that employed at the outlet from the heating coil may be utilized in the first reaction chamber and may be substantially equalized or somewhat reduced in the second reaction chamber. The heating coil of the coking system may employ an outlet conversion 30 temperature ranging, for example, from 900 to 1050° F., preferably with a superatmospheric pressure of from 100 to 500 pounds, or thereabouts, per square inch which pressure may be substantially equalized or somewhat reduced 35 in the succeeding coking chamber. The vaporizing chamber is preferably operated at a substantially reduced pressure relative to that employed in the last reaction chamber, ranging, for example, from 100 pounds, or thereabouts, per square inch down to substantially atmospheric pressure. The fractionating, condensing and collecting portions of the system may employ pressures substantially the same or somewhat lower 40 than that utilized in the vaporizing chamber. 45 50

The following is a specific example of one of the many possible operations of the process of the present invention as it may be accomplished in an apparatus of the character illustrated and above described, utilizing as charging stock a 55 Mid-Continent topped crude of about 30° A. P. I. gravity, which is supplied to the vaporizing chamber: Reflux condensate from the fractionator of the cracking system, including the components of the charging stock vaporized in the vaporizing chamber and subsequently condensed in the fractionator, as well as the intermediate conversion products of the process which are condensed in the fractionator as reflux condensate, is subjected in the heating coil of the cracking system 60 to an outlet conversion temperature of approximately 950° F. at a superatmospheric pressure of about 350 pounds per square inch. This pressure is substantially equalized in the succeeding reaction chamber. The residual liquid conversion products from the first reaction chamber are quickly heated in a separate heating coil, together with residual liquid from the vaporizing chamber (the latter including some high-boiling components of the charging stock re- 65 70 75

maining unvaporized in this zone) to an outlet temperature of approximately 1000° F. at a superatmospheric pressure of about 250 pounds per square inch. Substantially the same pressure 5 is maintained in the coking chamber and in the second reaction chamber, to which vaporous products from the coking chamber and from the first mentioned reaction chamber are supplied for further conversion. The vaporizing chamber 10 is operated at a superatmospheric pressure of approximately 30 pounds per square inch. This pressure is substantially equalized in the succeeding fractionating, condensing and collecting portions of the system. This operation may produce, per barrel of charging stock, approximately 68 per cent of motor fuel having an antiknock 15 value equivalent to an octane number of approximately 70 by the motor method and approximately 75 pounds of low volatile coke of substantially uniform quality, the remainder being chargeable, principally, to uncondensable gas and loss.

I claim as my invention:

1. In a process for the conversion of hydrocarbon oil wherein the oil is subjected to cracking conditions of elevated temperature and superatmospheric pressure, the resulting vaporous and liquid conversion products separated and the latter subsequently subjected to coking at a temperature of from 900 to 1050° F. and under substantial superatmospheric pressure of from 100 to 500 pounds per square inch, the improvement which comprises commingling the vaporous products from the coking operation with the vaporous 35 products previously separated from the liquid conversion products subjected to said coking and subjecting the commingled vapors, in a zone maintained at conversion temperature, to continued cracking at substantial superatmospheric 40 pressure for a predetermined time without additional heating.

2. In a process for the conversion of hydrocarbon oil wherein the oil is subjected to cracking conditions of elevated temperature and superatmospheric pressure, the resulting vaporous and liquid conversion products separated, the latter subjected to additional heating and coking at a temperature of from 900 to 1050° F. and under substantial superatmospheric pressure of from 100 to 500 pounds per square inch, the improvement which comprises commingling the vaporous products from the coking operation with the vaporous products previously separated from the liquid conversion products subjected to said coking and subjecting the commingled vapors, in a zone maintained at conversion temperature, to continued cracking at substantial superatmospheric pressure for a predetermined time without additional heating.

3. In a process for the conversion of hydrocarbon oils wherein an oil is subjected to cracking conditions of elevated temperature and superatmospheric pressure, the resulting vaporous and liquid conversion products separated and the latter subsequently subjected to coking at high temperature of from 900 to 1050° F. and substantial superatmospheric pressure of from 100 to 500 pounds per square inch, the improvement which comprises commingling the vaporous products from the coking operation with the vaporous products previously separated from the liquid conversion products subjected to said coking, subjecting the commingled vapors, in a zone maintained at conversion temperature, to continued cracking at substantial superatmospheric

pressure for a predetermined time without additional heating, separating the resulting vaporous and liquid conversion products, subjecting the former to fractionation for the formation of reflux condensate, returning the reflux condensate to the first named cracking, subjecting fractionated vapors of the desired end-boiling point to condensation and recovering the resulting products.

4. In a process for the conversion of hydrocarbon oils wherein an oil is subjected to cracking conditions of elevated temperature and superatmospheric pressure in a heating coil, the heated products introduced into an enlarged reaction chamber, also maintained at superatmospheric pressure, wherein vaporous and liquid conversion products separate and wherein the vapors are subjected to continued conversion time, the improvement which comprises withdrawing residual liquid conversion products from the reaction chamber, heating the same in a separate heating coil to a temperature sufficiently high to effect their subsequent reduction to coke without allowing them sufficient time in the heating coil to permit the excessive formation and deposition of coke in this zone, introducing the highly heated residual liquid into a coking chamber, maintaining said separate coil and coking chamber under substantial superatmospheric pressure of from 100 to 500 pounds per square inch, reducing the heated residual liquid to coke in the coking chamber, withdrawing hot vaporous products from the coking chamber, commingling the same with the vaporous conversion products from the reaction chamber and subjecting the commingled vapors to continued cracking at substantial superatmospheric pressure in a separate unheated reaction chamber maintained at conversion temperature by the heat of the vaporous products, separating the resulting vaporous and liquid conversion products, subjecting the vapors to fractionation, whereby their insufficiently converted components are condensed as reflux condensate, returning the reflux condensate to the first mentioned heating coil for further conversion, subjecting fractionated vapors of the desired end-boiling point to condensation and collecting the resulting distillate.

5. In a process for the conversion of hydrocarbon oils wherein an oil is subjected to cracking conditions of elevated temperature and superatmospheric pressure in a heating coil, the heated products introduced into an enlarged reaction chamber, also maintained at superatmospheric pressure, wherein vaporous and liquid conversion products separate and the vapors are subjected to continued conversion time, the improvement which comprises withdrawing residual liquid conversion products from the reaction chamber, heating the same in a separate heating coil to a temperature sufficiently high to effect their subsequent reduction to coke without allowing them sufficient time in the heating coil to permit the excessive formation and deposition of coke in this zone, introducing the highly heated residual liquid into a coking chamber, maintaining said separate coil and coking chamber under substantial superatmospheric pressure of from 100 to 500 pounds per square inch, reducing the heated residual liquid to coke in the coking chamber, withdrawing hot vaporous products from the coking chamber, commingling the same with the vaporous conversion products from the reaction chamber and subjecting the commingled vapors

to continued cracking at substantial superatmospheric pressure in a separate unheated reaction chamber maintained at conversion temperature by the heat of the vaporous products, separating 5 the resulting vaporous and liquid conversion products, subjecting the latter to further vaporization at substantially reduced pressure, subjecting the vaporous conversion products, including those evolved by said further vaporization, to 10 fractionation whereby their insufficiently converted components are condensed as reflux condensate, returning the reflux condensate to the first mentioned heating coil for further conversion, subjecting fractionated vapors of the 15 desired end-boiling point to condensation and collecting the resulting distillate.

6. A process of the character defined in claim 5 wherein residual liquid resulting from said further vaporization of the liquid conversion products 20 from the last mentioned reaction chamber are returned to the coking chamber for further treatment.

7. A process of the character defined in claim 5 wherein residual liquid resulting from said further vaporization of the liquid conversion products 25 from the last mentioned reaction chamber are returned to the heating coil of the coking system.

8. A process of the character defined in claim 30 5 wherein hydrocarbon oil charging stock for the process is supplied to the first mentioned heating coil.

9. A process of the character defined in claim 35 5 wherein hydrocarbon oil charging stock for the process, comprising an oil of relatively high-boiling characteristics, is supplied to the heating coil of the coking system.

10. A process of the character defined in claim 40 5 wherein hydrocarbon oil charging stock for the process is supplied to the vaporizing chamber.

11. A process of the character defined in claim 45 5 wherein hydrocarbon oil charging stock for the process is supplied to the fractionating zone.

12. A conversion process which comprises subjecting 45 hydrocarbon oil to cracking conditions of temperature and pressure in a cracking zone, separately removing vapors and unvaporized oil from said zone, heating and coking the unvaporized oil at temperatures of from 900 to 1050° F. and under pressures of from 100 to 500 pounds 50 per square inch, combining vapors evolved by

such heating and coking of the unvaporized oil with vapors removed from the cracking zone, subjecting the commingled vapors, in a zone maintained at conversion temperature to continued cracking under superatmospheric pressure by the heat contained in the vapors and without additional heating thereof, and fractionating and condensing the vaporous products of said continued conversion.

13. A conversion process which comprises subjecting hydrocarbon oil to cracking conditions of temperature and pressure in a cracking zone, separately removing vapors and unvaporized oil from said zone, passing the unvaporized oil through a heating coil and heating the same 10 therein to a temperature of from 900 to 1050° F., discharging the thus heated oil into a coking zone and distilling the same to coke therein, maintaining said coil and coking zone under pressure of from 100 to 500 pounds per square inch, 15 combining the vapors evolved in the coking zone with those removed from the cracking zone, subjecting the commingled vapors, in a zone maintained at conversion temperature to continued cracking under superatmospheric pressure by the 20 heat contained in the vapors and without additional heating thereof, and fractionating and condensing the vaporous products of said continued conversion.

14. A process for cracking hydrocarbon oil 30 which comprises passing the oil through a heating zone and heating the same therein sufficiently to vaporize a substantial portion thereof, introducing the heated oil into an enlarged separating zone and therein separating the same into 35 vapors and liquid, removing the liquid from the separating zone and cracking the same at a temperature of from 900 to 1050° F. under a pressure of from 100 to 500 pounds per square inch, introducing resultant cracked vapors and the 40 first-named vapors to an unheated reaction zone maintained at cracking temperature by the heat of the vapors, subjecting the commingled vapors to cracking under superatmospheric pressure in the reaction zone by the heat contained in the 45 vapors and without additional heating thereof, and then removing the vapors from the reaction zone and subjecting the same to fractionation and condensation.

KENNETH SWARTWOOD.
